FRAME OF AN OUTDOOR BABY SEAT

Cedric C. Stack, Elwood, Ind.

Application September 5, 1952, Serial No. 21,344

Term of patent 14 years

(Cl. D15—1)

To all whom it may concern:

Be it known that I, Cedric C. Stack, a citizen of the United States and a resident of Elwood, county of Madison, and State of Indiana, have invented a new, original, and ornamental Design for a Frame of an Outdoor Baby Seat, of which the following is a specification, reference being had to the accompanying drawing, forming a part thereof, in which Fig. 1 is a perspective view of a frame of an outdoor baby seat, showing my new design; and Fig. 2 is a top view thereof on substantially the scale of Fig. 1.

I claim:

The ornamental design for a frame of an outdoor baby seat, substantially as shown.

CEDRIC C. STACK.
